Application August 18, 1936, Serial No. 96,704
In Great Britain August 22, 1935

9 Claims. (Cl. 40—130)

The present invention relates to signs for advertising and other purposes which comprises luminous electric discharge tubes operated from high frequency current.

5 The present invention has for its object to provide a very simple and cheap arrangement whereby the text of the sign may be easily altered and wherein any desired wording may be easily and cheaply built up from a supporting base and interchangeable standard letters.

10 According to the present invention a sign comprises a supporting base which is provided with a plurality of sockets at equal distances along its length, said sockets being connected to a source 15 of high frequency current and being adapted to receive a part or parts of a luminous electric discharge tube and constituting the sole means for supplying the energy to the discharge tube.

15 The letters or symbols are made to standard dimensions so that any letter or symbol of any size, may be plugged into the standardized supporting base. The discharge tubes may have internal electrodes, in which case connection to the electrodes is effected on inserting the tube into 20 the sockets. On the other hand, the discharge tube may have no internal electrodes, in which case the sockets are made of conducting material and constitute external electrodes for the discharge tube when the tube is inserted in the 25 supporting base. The several sockets in the supporting base may be all connected to one terminal of the high frequency generator or they may 30 be variously connected to different terminals thereof.

35 The base preferably comprises or is surrounded with a metallic screen, in order to prevent interference with local radio reception. The screen may be earthed.

40 In order that the invention may be more clearly understood reference will now be made, by way of example, to the accompanying drawing, in which

45 Fig. 1 shows a perspective view of one form of the invention.

Fig. 2 shows a section along the line A—A in Fig. 1.

Fig. 3 shows a side view.

Fig. 4 shows a discharge tube with a special background construction.

50 Fig. 5 shows a section along the line B—B in Fig. 4.

Figs. 6 and 7 show modifications of Fig. 5.

Referring to Figs. 1, 2 and 3 of the drawing, the supporting base comprises a square casing 1 which is preferably of metal so as to constitute

a screen for the high frequency conductors. Supported within this casing is a strip of insulating material 2, which extends substantially the whole length of the casing. Holes are drilled in the upper surface of this insulating strip into which metallic tubular sockets 3 are inserted and held by means of the screws 4. The sockets 3 are insulated from the metal casing 1 by means of the insulating collars 5. The sockets are inserted in the insulating strip at equal distances along its length and the supporting base is made as long as desired to accommodate the sign to be displayed.

5 The end of the casing may be closed and provided with contact plugs 6 to which are electrically connected the sockets 3 by wires which pass within the casing and connect to the screws 4. All the sockets may be connected to one plug terminal 6, or, alternate sockets may be connected to separate plugs. The plug 6 may be 20 inserted in the counter-part sockets in the high frequency generator 7 so as to feed the tube sockets with high frequency current.

15 The other end of the supporting base is preferably provided with counter-part connecting 25 sockets electrically connected to the plugs 6 so that several base units may be connected together by merely inserting the plug 6 at the end of one unit into the corresponding counter-part connecting sockets at the end of another unit.

20 The luminous electric discharge tubes 8, 9, 10 are made in standard sizes, the distance between the feet of which correspond to the distances between various pairs of sockets. The letters may be made in different heights, for example, 6 35 inches, 12 inches and 18 inches, the 6 inch letters being secured between two adjacent terminals, the 12 inch letters fitting into every alternate terminal, and the ends of the 18 inch letters fitting into every fourth terminal, as shown 40 in Fig. 1.

25 Since high frequency current is used to energize the discharge tubes it is only necessary to insert one end of the discharge tube into a socket in order to make it light and hence for letters 45 such as "I" only a single upright tube is necessary which is inserted into a single socket. The tube is illuminated although only one end is supplied with current due to the capacity between the other parts of the tube and earth.

30 The casing 1 may be about 2 inches square and of any desired length, and since it is unnecessary to provide the discharge tubes with internal electrodes a very simple sign is produced in which the letters may be readily interchanged. More- 55

over, since the discharge tubes have no internal electrodes, they are very simple and cheap to manufacture.

As will be seen, the sockets constitute the sole means for supplying the high frequency current to the discharge tubes. The metal casing 1 is preferably earthed.

Various modifications may be made without departing from the invention. For example the high frequency generator may be arranged within the supporting base, or, alternatively, may be located at a point remote from the base.

When using certain letters or symbols, such as the letter "E", in the supporting base, difficulty may be experienced in getting the luminous discharge to extend through all the limbs so as to give uniform illumination. This difficulty may be overcome by providing the discharge tube with a background which forms or contains one or more conducting paths arranged to feed the high frequency current to the tube at the desired points.

The background may be formed of insulating material in which the conducting paths are embedded. Alternatively, it may consist of conducting material or it may be composed in part of conducting material and in part of insulating material.

The background may be visible or it may be concealed behind the tube or it may partially envelope the tube leaving an opening on one side only through which the tube is visible. The background may support the tube or form a part of the support therefor. Alternatively, or in addition, the tube and background may be supported on a common base.

One method of constructing a discharge tube with a background is shown in Figs. 4 and 5, in which the luminous electric discharge tube 11 is shown in the form of a letter "E". High frequency current is applied to the tube at the projection 12 when the tube is inserted in the supporting base. In the example shown no internal electrodes are provided.

In order to cause the discharge to pass uniformly through all the limbs of the tube the tube is provided with a background 13 of insulating material in which is embedded a conductor 14 terminating in the electrodes 15, 16 and 17 arranged at the surface of the insulating material and adapted to lie adjacent the glass of the discharge tube at the ends of the limbs as shown. The conductor is connected to a metallic contact 18 which fits into another socket in the supporting base.

The high frequency current is fed electrostatically to the tube at the points 12, 15, 16 and 17 and it will be uniformly illuminated.

Of course, the tube may be provided with internal electrodes if desired, in which case the internal electrode 19 (see Fig. 6) is connected to a terminal 20 on the rear surface of the tube which is adapted to engage with a contact 15' embedded in the surface of the insulating background 13.

Instead of feeding the tube at various points it may be fed throughout its length by providing a conducting background as shown in Fig. 7. In this figure the metallic background 21 is connected to the terminal 18 whereby the high frequency current is electrostatically fed through the tube throughout its length. In an alternative modification the conductor 14 (Fig. 4) could be located on the surface of the insulating material adjacent the tubes whereby the same effect of feeding the tube throughout its length may be obtained.

Since when using high frequency current the

tubes may be illuminated by connecting it to only one terminal of the high frequency generator, the projection 12 may be dispensed with and the tube illuminated by feeding the high frequency current to the tube solely through the terminal 18 which is connected to feed the tube at one or more points.

I claim:—

1. A sign comprising a supporting base, a plurality of equally spaced sockets carried by said supporting base, a high frequency generator connected to supply high frequency current to said sockets, and luminous electric discharge tubes having the form of the characters to be displayed, the ends of which tubes are so dimensioned and spaced that the tubes may be interchangeably mounted in said sockets in order to feed the tubes from the high frequency current, said sockets constituting the sole means for supplying the high frequency current to said tubes. 20

2. A sign comprising a supporting base, a plurality of conducting sockets equally spaced along the length of said base, a high frequency generator connected to feed high frequency current to said sockets, and a plurality of luminous electric discharge tubes having no internal electrodes and having the form of the characters to be displayed, the ends of said tubes being so dimensioned and spaced that the tubes may be interchangeably fitted within said sockets, said sockets constituting external electrodes for supplying the high frequency current to the discharge tubes. 25

3. A sign comprising a supporting base, a plurality of equally spaced sockets carried by said supporting base, a high frequency generator connected to supply high frequency current to said sockets, luminous electric discharge tubes having the form of the characters to be displayed, the ends of which tubes are so dimensioned and spaced that the tubes may be interchangeably mounted in said sockets in order to feed the tubes from the high frequency current, and a metallic screen enclosing the conductive parts to which high frequency current is fed. 45

4. A sign comprising a supporting base, a plurality of conducting sockets equally spaced along the length of said base, a high frequency generator connected to feed high frequency current to said sockets, a plurality of luminous electric discharge tubes having no internal electrodes and having the form of the characters to be displayed, the ends of said tubes being so dimensioned and spaced that the tubes may be interchangeably fitted within said sockets, said sockets constituting external electrodes for supplying the high frequency current to the discharge tubes, and a metallic screen enclosing the conductive parts to which high frequency current is fed. 55

5. A supporting base comprising a metallic tubular casing, a plurality of equally spaced apertures formed in one surface of said casing, a tubular metallic socket arranged beneath each of said apertures, insulating material carrying said sockets and insulatingly supporting them from the casing and from one another, and a conductor connected to said sockets for supplying high frequency energy thereto. 60

6. A sign comprising a metallic tubular casing, a plurality of equally spaced apertures formed in one surface of said casing, a tubular metallic socket arranged beneath each of said apertures, insulating material carrying said sockets and insulatingly supporting them from the casing and from one another, a high frequency generator, a 70

75

conductor connecting the output from said generator to said sockets, a plurality of luminous electric discharge tubes having the form of the characters to be displayed, the ends of which are so dimensioned and spaced that the tubes may be interchangeably mounted in said sockets.

5. A sign comprising a metallic tubular casing, a plurality of equally spaced apertures formed in one surface of said casing, a tubular metallic socket arranged beneath each of said apertures, insulating material carrying said sockets and insulatingly supporting them from the casing and from one another, a high frequency generator, a conductor connecting the output from said generator to said sockets, a plurality of luminous electric discharge tubes having no internal electrodes and having the form of characters to be displayed, the ends of which are so dimensioned and spaced that the tubes may be interchangeably mounted in said sockets, said sockets constituting external electrodes for the discharge tubes.

10. A sign comprising a metallic tube of rectangular cross section, a plurality of apertures in one surface of said tube, a strip of insulating material arranged within said metallic tube and beneath the apertures therein, a plurality of smaller apertures in said insulating material and arranged below the apertures in the tube, a metallic socket arranged within each of said apertures in the insulating strip, and an electric conductor connected to said sockets.

15. A sign comprising a metallic tube of rectangular cross section, a plurality of apertures in one surface of said tube, a strip of insulating material arranged within said metallic tube and beneath the apertures therein, a plurality of smaller apertures in said insulating material and arranged below the apertures in the tube, a metallic socket arranged within each of said apertures in the insulating strip, and an electric conductor connected to said sockets.

20. A sign comprising a metallic tube of rectangular cross section, a plurality of apertures in one surface of said tube, a strip of insulating material arranged within said metallic tube and beneath the apertures therein, a plurality of smaller apertures in said insulating material and arranged below the apertures in the tube, a metallic socket arranged within each of said apertures in the insulating strip, an electric conductor connected to said sockets, a high frequency generator, a conductor connecting the output from said generator to said sockets, a plurality of luminous electric discharge tubes having the form of the characters to be displayed, the ends of which are so dimensioned and spaced that the tubes may be interchangeably mounted in said sockets.
